(57) **CLAIM**

The ornamental design for a flatware handle, as shown and described.

DESCRIPTION

FIG. 1 is a perspective view of flatware handle showing my new design as applied to a first item of flatware;

FIG. 2 is an elevational view thereof;

FIG. 3 is an enlarged perspective view of an illustrative portion of the design;

FIG. 4 is a perspective view of the design as applied to a second item of flatware; and

FIG. 5 is an elevational view thereof; and,

FIG. 6 is a partial cross-sectional view taken along line 6—6 in FIG. 2, further depicting the design.

The broken lines shown in the drawings are for illustration purposes only and form no part of the claimed design.

1 Claim, 4 Drawing Sheets

FIG. 3

FIG. 6
